ATTORNEY

UNITED STATES PATENT OFFICE.

AGNES H. GRIFFIN, OF NEW YORK, N. Y.

WRIST LOCK.

Application filed April 2, 1923. Serial No. 629,499.

To all whom it may concern:

Be it known that I, AGNES H. GRIFFIN, a citizen of the United States, residing at New York city, in the county of New York and State of New York, have invented new and useful Improvements in Wrist Locks, of which the following is a specification.

This invention relates to wrist locks for use in connection with purse or bag handles, 10 and more particularly to a wrist lock for ladies' mesh bags having a chain or cord handle.

The principal object of the invention is the provision of a wrist lock device adapted 15 to be passed over a looped end of a handle of a ladies' bag and having means carried by the device for engagement with the side leads of the handle below the bight thereof for locking the handle upon the wrist of 20 the wearer.

Another object of the invention is the provision of a wrist lock device adapted to be associated with the chain handle of a purse or bag whereby the weight of the bag 25 will cause the device to automatically adjust itself upon the handle to form a loop for locking the bag upon the wrist of an individual.

A further object of the invention is to 30 provide a wrist lock device which can be easily applied to or removed from a bag handle without disconnecting the handle from the bag.

A still further object of the invention is 35 the provision of a wrist lock device which is highly ornamental and attractive and capable of being made of various materials to match the material of the bag.

A still further object is to provide a wrist 40 lock device which when applied to the handle of a bag will not interfere with the movement of the hand of the wrist to which it is applied, when it is desired to open the bag with this particular hand.

Another object is to provide a wrist lock 45 device which is simple in construction, cheap to manufacture and highly efficient for the purpose intended.

With these and other objects in view, the 50 invention relates to certain novel construction and combination and arrangement of parts, the essential features of which are hereinafter fully described in the specification and pointed out in the claims and illus-

trated in the accompanying drawing, in 55 which:—

Figure 1 is a perspective view of a ladies' mesh bag showing my wrist lock in use.

Figure 2 is a plan view of the wrist lock 60 device.

Figure 3 is a sectional view on the line 3—3 of Figure 2.

Figure 4 is a plan view of a slightly modified form of device and

Figure 5 is a similar view of a further 65 modification.

I am aware that prior devices of this nature have been on the market but all of these devices are used upon strap handles and must be adjusted manually to form the 70 wrist loop at the top of the bag handle. It is therefore my intention to provide a device of this nature for use upon ladies' mesh bags wherein the device is automatically adjustable.

Like characters of reference refer to like parts in all views. Referring more particularly to the drawing, the reference numeral 10 designates a ladies' mesh bag, having the 75 upper chain handle 11 connected thereto. I 80 find that my invention is best used in connection with a chain handle but the same could be used upon a flexible silk cord handle if desired.

With particular reference to my preferred 85 form, it will be seen that the reference numeral 12 designates my improved wrist lock device in its entirety, the same being made of any suitable material and comprising two identical sections 13 and 14. These 90 sections are each made from a single piece of material to form a relatively long

straight portion 15, the end of each piece being bent upon itself to form a resilient 95 finger 16. These fingers 16 have their extremities rounded as at 17 for contact with the straight portions 15 of the sections 13 and 14, thereby forming normally closed loops or eyes 18, adapted to receive the leads of the handle of the bag. Each section 13 100 and 14 is riveted together at the extremity of the flat straight portion 15 with the looped portion of the other section as at 19.

In practice, when it is desired to apply the device to the handle, the leads of the 105 same are passed under the portions 17 and into the loops 18, the fingers 16 contacting with the portion 15 to close the loops and

prevent accidental removal of the device from the handle. The device now forms the top of the handle into a wrist loop 20 for the accommodation of the wrist, and by 5 reason of the weight of the bag, together with the spread of the handle leads, the device will automatically ride up the chain and into contact with a wrist of the wearer. It will thus be seen that the lock device is 10 automatically adjustable to various sized wrists and that it is only necessary to slide the device downward to enlarge the loop 20 for removing the bag from the wrist. Furthermore it will be seen that the bag 15 may be opened and access had to the interior without removing the same from the wrist.

If desired the exterior surfaces of the portions 15 may be provided with a monogram 20 or set with any desired jewel.

In Figure 4, I have shown a slightly modified form of wrist lock device 21, comprising an endless body member 22, and riveted as at 23 to one side of the body member 25 is a flat spring 24 having a pair of humps 25 for co-action the other side of said body member thereby defining a pair of eyes 26 similar to those in the preferred form. The extremities of the spring 24 are rounded as 30 at 27 so as not to interfere with the sliding movement of the device when applied to the handle.

In Figure 5, there is shown a further modification which is quite similar to the 35 form shown in Figure 4 with the exception that the ends of the spring 24 are curved upward as at 28 to lie in close contact with the ends of the body member 21.

While there has been shown and described what is considered to be the best embodiment of my invention, it is understood that no limitation is necessarily made to the precise structural details herein exhibited, but that changes, alterations and modifications as come within the claims may be resorted to when desired.

What is claimed as new is:—

1. A device of the class described, the combination with the flexible handle of a bag, a wrist lock member, means on said member for detachably connecting the same with the closed portion of the handle whereby said lock member will be caused to automatically ride up the handle for forming an adjustable loop at the top thereof.

2. As a new article of manufacture for use in connection with the flexible handle of a bag comprising an elongated body member, a pair of fingers co-acting with said body member for defining a pair of eyes at opposite ends thereof for detachable connection with the leads of said handle to automatically ride up the leads to form an adjustable loop at the top thereof.

3. A wrist lock device for hand bags comprising a body adapted to permit of the passage therethrough of the entire looped end of the handle of the bag, and means carried by the member engagable with the side leads of the handle below the bight thereof, said means including a pair of eyes constituting spring pressed fingers.

In testimony whereof I have affixed my signature.

AGNES H. GRIFFIN.
